ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

AUTOMATIC REVERSIBLE RIBBON-FEED.

1,257,401.

Specification of Letters Patent. Patented Feb. 26, 1918.

Application filed June 1, 1915. Serial No. 31,332.

To all whom it may concern:

Be it known that I, ALVAH C. ROEBUCK, a citizen of the United States, residing at Woodstock, in the county of McHenry and 5 State of Illinois, have invented certain new and useful Improvements in Automatic Reversible Ribbon-Feeds, of which the following is a specification.

This invention relates to typewriters, and 10 more particularly to the ribbon feeding mechanism with parts for automatically reversing the feeding mechanism when the ribbon is nearly unwound from one of the ribbon spools.

15 The principal object of the invention is to provide a simple, reliable and efficient mechanism for effecting the automatic reverse of the typewriter ribbon, and the invention consists in the construction, combination and 20 arrangement of parts for accomplishing this result. Other objects of the invention will appear hereinafter.

In the drawings, Figure 1 is a plan view viewed from the under side, of the preferred 25 embodiment of my invention; Fig. 2 is a perspective of one of the ribbon spools; Fig. 3 is a side elevation of one of the ribbon spools with parts broken away to show the 30 operating mechanism; Fig. 4 is a sectional side view of one of the ribbon spools; Fig. 5 is a sectional view on the line 5—5 of Fig. 1, and Fig. 6 is a perspective of a reversing lever.

One of the principal advantages of this 35 automatic ribbon reverse mechanism, in addition to simplicity and economy of construction, is that there is no additional strain on the ribbon during the reversing operation, the reverse being accomplished by the 40 feeding mechanism. Also the reversing is done much more quickly than many forms of mechanism for this purpose which prevents a prolonged operation of the type on the same spot of the ribbon. The action of 45 this reversing mechanism is so light that it does not materially increase the tension on any of the operating parts and does not necessitate a heavier touch on the key buttons of the type bar levers to any appreciable 50 extent.

Referring now more particularly to the drawings, the numeral 1 designates generally the top frame of a typewriter to which the apparatus is attached, the mechanism 55 being viewed from the under side in Fig. 1.

Secured to this portion of the frame is a type bar segment 2 in which the type bars are pivoted in the ordinary manner, and at the rear of the segment is a universal bar 3 connected to a frame 4 which oscillates with 60 the universal bar to operate the escapement mechanism (not shown) in the well known manner.

Mounted in brackets 5 depending from the plate is a longitudinally movable shaft 6, 65 and freely mounted upon the shaft between the brackets is a sleeve 7. To the sleeve is secured a collar 8 which has a plate 9 (see Fig. 5) by means of which it is connected to the oscillating frame 4 so that the oscillation 70 of the frame will cause a rotary movement to be imparted to the sleeve 7. Adjacent each end of the sleeve is a collar 10 connected to a feeding pawl 11 so that reciprocating movement will be given to the pawl 75 as the sleeve is oscillated. Mounted on the plate 1 adjacent each feeding pawl is a detent pawl 12 and connected to the pawls are springs 13 and 14 which tend to draw them in connection with a ribbon feeding ratchet 80 wheel 15.

A ribbon spool cover 16 is secured to the top of the frame 1 at each side thereof preferably by means of a perforated stud 17 which is secured to the spool cover and has 85 a threaded extension 18 extending through the plate 1. A hexagonal nut 19 is provided in the extending threaded sleeve which engages the threaded extension 18 and thereby holds the spool cover, stud and the cover in 90 place on the plate 1. This nut 19 and its sleeve also forms a bearing for a rotatable hub 20 to which is secured the ratchet feed wheel 15, a cam 21 and a gear 22 separated from the cam by a collar 23. This hub 20 is 95 freely rotatable and both of the ratchet feed wheels 15 are held in continual engagement with the feeding and detent pawls 11 and 12 so that they are operated continuously in the same direction when the typewriter is in 100 operation.

A ribbon spool shaft 24 extends through the cover stud 17 and is freely rotatable therein. It is held in place by a collar 25 secured to it above the stud 17 and has a perforation 26 at the lower end in which a rod 27 is slidable, the collar 25 being provided with a laterally opening recess through which the upper bent end 28 of the rod 27 extends. The opening for the upper end of 110

the rod 27 permits the rod to slide up and down, and pivoted to the collar 25 is a perforated yoke 29 which engages the bent end 28 of the rod, and the yoke has a finger 30 which extends upwardly for engagement by the ribbon to control the position of the slide rod. The spool shaft 24 is held in place at its lower end by means of a hub 31 threaded on the lower end of the rod to 10 which is secured a gear 32 which is slightly less in diameter than the gear 22 mounted on the hub 20 but preferably has the same number of teeth. At the lower end of the slide rod 27 is a collar 33 preferably held 15 in place by a nut 34. From this description it is obvious that the slide rod 27 rotates with the ribbon spool shaft 24 but may slide longitudinally therein and the ribbon spool shaft is freely rotatable within the ribbon 20 spool stud 17 and carries the gear 32 which is fixed to the shaft. The hub 20 is intermittently rotated in the same direction when the typewriter is operated carrying with it the ratchet 15, the cam 21, the gear 22, which 25 is slightly larger in diameter than the gear 32.

A ribbon spool is shown in perspective in Fig. 2 and in section in Fig. 4 and comprises a perforated hub 35 which slips over the 30 ribbon spool shaft 24 and has a projection 36 which engages in a corresponding hole in the collar 25 for rotating the spool with the spool shaft. A nut 37 at the top of the spool shaft holds the spool in place. The hub 35 is formed with a recess 38 and one 35 end of the ribbon spool is provided with an aperture 39 corresponding to the recess through which the finger 30 of the pivoted yoke 29 is adapted to extend. When ribbon is wound about the spool in engagement with the finger 30 the yoke is pressed to its uppermost position carrying with it the slide rod 27 by reason of the engagement of its bent end 28 with the yoke 29. As soon as 40 the ribbon is unwound from the spool so that there is nothing to hold the finger 30 in place the rod 27 and the yoke 29 drop to the lowermost position for actuating the reverse mechanism as hereinafter described. 45 At each side of the plate, is a boss 40 which supports a rotatable stud 41 upon which is pivoted at right angles to the axis of the stud a yoke 42 (see Fig. 6) having extending arms 43 and 44 spaced apart, the 50 former carrying a roller 45 and the latter being formed with a head 46 adapted to be engaged in the collar 33 of the rod 27. The stud 41 is provided with a projection 47 to limit the downward movement of the yoke 55 42. Also secured to each stud shaft 41 is a lever 48 which carries on one end a freely rotatable pinion 49 of considerable length which adapts it to make connection between the gears 22 and 32 carried by the hubs 20 60 and 31, respectively. Each lever 48 is se-

cured to its stud shaft 41 and the latter to the frame by a fastening device 50 so that when the stud shaft 41 is oscillated the lever 48 is carried with it. The stud shafts are oscillated by means of yoke members 42, 70 each of which has one arm in engagement with the collar 33 of its slide rod 27, and the roller 45 of each yoke member is adapted to engage its cam 21 depending upon the position of the slide rod. If the slide rod 75 is in its uppermost position, as shown by the left hand side of Fig. 1 and by Fig. 3, the roller 45 does not engage its cam 21 but as soon as the slide rod falls the roller 45 is moved by the yoke to engage the cam 21, or 80 if the cam is in the position as shown by the left hand portion of Fig. 1 the roller will rest on the surface of the cam until the cam is rotated by the ratchet wheel 15 to a position where the roller will fall and be engaged by the cam. The engagement of the roller 45 of a yoke member by its cam 21 causes the oscillation of the yoke and the corresponding oscillation of the lever 48 thereby moving the pinion 49 toward the 90 gears 22 and 32. Both of the levers 48 are connected by means of projections 51 with the longitudinally movable rod 6 so that the movement of one of the levers 48 causes a corresponding movement of the other one. 95 One of these levers, however, the left hand lever in Fig. 1, is formed with an angular extremity having angular portions 52 and 53 on opposite sides of the apex. Pivoted on the plate 1 adjacent this extremity is a bell 100 crank 54, one end having a roller 55 adapted to engage the angular portions and the other connected to a spring 56 for holding the bell crank in such engagement. The parts are so proportioned that when the roller 45, which 105 does the reversing, has not quite reached the topmost portion of its cam 21 its pinion 49 will be some distance away from the gears 22 and 32 and the roller 55 of the bell crank will be resting upon the point or apex of 110 the extremity of lever 48 between the angular portions 52 and 53. Then when the roller on the lever 48 reaches the topmost point of its cam 21, the roller 55 on bell crank 54 passes over the apex of the lever 115 48 and the action of the spring 56 attached to the bell crank and the action of the roller 55 on the cam surface 52 positively throws the pinion 49 into mesh with the gear 22. The object of having one gear 32 slightly 120 smaller in diameter than the gear 22 is to prevent the pinion 49 from locking when it is sprung into position upon the reversing movement. It will be noted that the teeth of these gears are pointed but still it might 125 happen that the point of the teeth of pinion would catch upon the point of the teeth of the gears and prevent their engagement. It will be noted that the pinion is free to rotate and the gear 22 is constantly rotated 130

when the typewriter is operated by means of the ratchet wheel 15 so that there is no question but that the pinion would mesh with the gear 22 but if the gears 22 and 32 were 5 of the same size there is a chance that when the pinion 49 is thrown toward them they might lock and prevent the operation of the whole machine. By having the gear 32 slightly less in diameter, even if the pinion 10 49 did engage the point of one of the teeth of the gear 32 the rotating gear 22 would engage the pinion, because the teeth are slightly longer than the teeth of the gear 32 and the pinion would be moved from the 15 locking position and would then be pressed by the spring 56 into engagement with both of the gears 22 and 32.

To limit the movement of the levers 48, and thereby to adjust their throw, since they 20 are both connected to the shaft 6, an adjustable set screw 57 is threaded to each of the brackets 5 in the path of movement of the corresponding lever 48.

In the operation, as before explained, the 25 ratchet wheels 15 are both driven intermittently in the same direction by the operation of the typewriter. The driving mechanisms are, of course, so arranged that when one spool driving mechanism is in operation the 30 other one is not in operation. Assuming that the right hand driving mechanism in Fig. 1 has been in operation and has wound the ribbon from the left hand spool the continued operation will cause the slide bar 27 35 of the left hand mechanism to drop which will operate the yoke 42 in the manner described to bring its roller 45 into engagement with the cam 21, whereupon the stud shaft 41 will be rotated carrying with it the 40 lever 48 to a position where its pinion 49 nearly engages the gear 22. At this time the apex of the lever 41 should be engaged by the roller 55 so that the least additional movement of the roller 45 on its cam will 45 cause the roller 55 to pass over the apex of the lever 48 thereby pressing or throwing the pinion 49 of the lever yieldingly in mesh with both of the gears 22 and 32. This action will move the right hand lever 48 and 50 its pinion out of engagement with its gears 22 and 32 and since the pinion 49 of the left hand mechanism will engage both of the gears 22 and 32 the rotation of the ratchet wheel 15 will be connected directly to the 55 ribbon spool shaft because the hubs 20 and 31 which carry the gears 22 and 32 respectively, are connected together by the pinion 49, thereby rotating the left hand ribbon spool shaft in a direction to wind the ribbon 60 upon its spool. The ribbon winding upon the spool will then engage the finger 30 and move the slide rod upwardly, which will raise the yoke member 42 so that the roller 45 is clear of its cam 21. The winding of 65 the ribbon upon the left hand spool shaft

will then continue until the reversing mechanism of the left hand spool is operated, whereupon the above described action will be automatically repeated for the right hand spool.

70

What I claim is:

1. In typewriter ribbon feeding mechanism, the combination with a pair of ribbon spool shafts, of a separate ratchet wheel for each shaft, means including a pawl and 75 ratchet for each wheel for separately rotating both wheels at the same time, and mechanism to connect one but not both wheels to its respective spool shaft at the same time.

2. In typewriter ribbon feeding mechanism, a pair of ribbon spool shafts, a separate ratchet wheel for each shaft, means including a pawl and ratchet for each wheel for separately rotating both wheels at the same time, and selective mechanism to positively connect one of the ratchets to its spool shaft to wind ribbon from the other shaft. 80 85

3. In typewriter ribbon feeding mechanism, separate ribbon spool ratchet wheels, means for separately operating them in unison, ribbon spool shafts, and separate selective means for each shaft for connecting one but not both of the wheels to its spool shaft and depending upon the ribbon wound upon the spool shaft for operation. 90 95

4. In typewriter ribbon feeding mechanism, separate ribbon spool ratchet wheels, means for separately operating them in unison, ribbon spool shaft, and separate selective means for each shaft joined for alternate operation and adapted to connect one but not both of the wheels to its spool shaft depending upon the ribbon wound upon the spool shaft for operation. 100

5. In typewriter ribbon feeding mechanism, the combination with a rotatable driving gear, a ribbon spool shaft, a gear mounted thereon adjacent the other gear, a pinion engageable with both of said gears for driving them in unison, a pivoted member for moving the pinion, and means comprising a cam for moving the pivoted member. 110

6. In typewriter ribbon feeding mechanism, the combination with a rotatable driving gear, a ribbon spool shaft, a gear mounted thereon adjacent the other gear, a pinion engageable with both of said gears for driving them in unison, a pivoted member for moving the pinion, a forked member for moving the lever, and means comprising a 120 cam for moving the forked member.

7. In typewriter ribbon feeding mechanism, a rotatable driving gear, a coaxial ribbon spool shaft, a gear secured to the shaft and less in diameter than the driving gear, 125 and a pinion engageable with both gears, and insured of such engagement with the gears by the rotation of the larger gear which sweeps the teeth of the pinion into mesh.

130

8. In typewriter ribbon feeding mechanism, a rotatable driving gear, a coaxial ribbon spool shaft, a gear secured to the shaft and less in diameter than the driving gear, and a pinion engageable with both gears, and means to press the pinion yieldingly toward the gears so that it will be swept into mesh therewith by the rotation of the larger gear.

9. In typewriter ribbon feeding mechanism, the combination with a rotatable driving gear, a ribbon spool shaft, a gear mounted thereon adjacent the other gear, a pinion adapted to be moved into engagement with both of the gears for driving them in unison, and means comprising a pivotally mounted yoke and a cam for operating the yoke to move the said pinion toward the said gears.

10. In typewriter ribbon feeding mechanism, the combination with a rotatable driving gear, of a ribbon spool shaft, a gear mounted thereon adjacent the other gear, a pinion adapted to be moved into engagement with both of the gears, means comprising a pivoted yoke for moving the pinion toward the gears, and means comprising a cam driven with the first mentioned gear for engaging the yoke to move the pinion.

11. In typewriter ribbon feeding mechanism, the combination with a driven gear wheel, of a ribbon spool shaft, a gear carried by the shaft adjacent the other gear, a pinion adapted to be moved into engagement with both of the gears, means comprising a yoke for moving the pinion toward the gears, and means comprising a slide bar controlled by the ribbon for operating the yoke member to move the pinion.

12. In typewriter ribbon feeding mechanism, the combination with a driven gear wheel, of a ribbon spool shaft, a gear carried by the shaft adjacent the other gear, a pinion adapted to be moved into engagement with both of the gears, means comprising a yoke for moving the pinion toward the gears, means comprising a cam driven by the first mentioned gear member for moving the yoke to move the pinion, and means comprising a slide bar controlled by the ribbon for moving the yoke member into and out of position where it will be engaged by the said cam.

13. In typewriter ribbon feeding mechanism, the combination with a driving gear, of a ribbon spool shaft, a gear carried thereby adjacent the other gear, a pinion adapted to engage both of the gears, a lever upon which the pinion is mounted, means comprising a yoke for moving the pinion toward the gears, and means comprising a spring-pressed bell crank free from the lever for engaging the lever and pressing the pinion into engagement with the gears.

14. In typewriter ribbon feeding mechanism, the combination with a driving gear,

15. In typewriter ribbon feeding mechanism, the combination with a driving gear, of a ribbon spool shaft, a gear carried thereby adjacent the other gear, a pinion adapted to engage both of the gears, a lever carrying a pinion on one end having faces at an angle to each other at the other end, means comprising a yoke for moving the pinion and the lever toward the said gears, operating means for the yoke, and a spring-pressed bell crank having a roller to engage the angular faces of the lever to press the pinion into and out of engagement with the said gears.

16. In automatic ribbon reversing mechanism, the combination with a driving gear rotatable in a constant direction, a ribbon spool shaft, a gear carried thereby adjacent the first mentioned gear, a pinion adapted to engage both of the gears at the same time, a lever carrying a pinion on one end and having faces substantially at right angles to each other at the other end, a yoke pivotally connected to the lever for moving it in the direction of the gears, means comprising a cam driven with the first mentioned gear to operate the yoke, means controlled by the ribbon for moving the yoke into and out of position to be engaged by the cam, and a spring-pressed lever having a roller to engage the said faces of the lever for moving it to press the pinion yieldingly into and out of engagement with the gears depending upon the position of the roller with respect to the said faces which it engages.

17. In automatic ribbon reversing mechanism, the combination with a driving gear, of a ribbon spool shaft, a gear carried thereby adjacent the other gear, a pinion adapted to be moved into engagement with both of the gears, a yoke for moving the pinion having two arms spaced apart and one provided with a roller, a cam for engaging the roller to oscillate the yoke, and means to move the said roller into and out of position to engage the cam comprising a slide bar controlled by the ribbon wound about the spool shaft having a collar which continually engages the other arm of the yoke member.

18. In automatic ribbon reversing mechanism, the combination with a pair of rotatable driving gears, a ribbon spool shaft corresponding to each gear, a gear mounted upon each shaft adjacent the driving gear, a pinion to engage the two gears adjacent each

ribbon spool shaft, a lever upon which each gear is mounted, a longitudinally movable shaft connecting the levers, means depending upon the amount of ribbon wound upon each ribbon spool shaft for moving the pinion of its shaft adjacent the said pair of gears and an extension on one of the said levers having faces at an angle to each other, and a spring-pressed bell crank with a roller 10 to engage the faces for pressing the lever and consequently both levers so that their pinions will be moved into and out of engagement with their respective gears to reverse the driving connection of the ribbon 15 spool shafts.

19. In automatic ribbon reversing mechanism, the combination with a longitudinally movable shaft, of a pair of ribbon spool shafts, means in connection with each ribbon spool shaft for rotating the shaft in one direction and comprising a rotatable driven member, an oscillatable sleeve through which the longitudinally movable shaft extends, means connecting the sleeve with both 25 of the said driven members to rotate them simultaneously, reversing mechanism in connection with each ribbon spool shaft comprising a lever of each feeding mechanism both connected to the longitudinally mov-

able shaft, one of the levers being formed 30 with faces at an angle to each other, and a spring-pressed member with a roller to engage the said faces to press the lever and the said longitudinally movable shaft yieldingly in a direction depending upon the face 35 against which the said roller bears.

20. In automatic ribbon reversing mechanism, the combination with a longitudinally movable shaft, of a pair of rotary driving members, means to operate the said members in unison, ribbon spool shafts, mechanism for connecting one but not both of the ribbon spool shafts to the said driving members at the same time comprising pivotally mounted levers both connected at one end to 40 the said longitudinally movable shaft, and an adjustable stop adjacent each end of the longitudinally movable shaft to limit the movement of one of the levers in the direction of the other lever.

In testimony whereof I have signed my name to this specification, in the presence of two subscribing witnesses, on this 28th day of May A. D. 1915.

ALVAH C. ROEBUCK.
